CLAIM

The ornamental design for a pill organizer, as shown and described.

DESCRIPTION

FIG. 1 is a perspective view of a pill organizer, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof showing the pill organizer when opened.

In the drawings, the broken lines are shown for illustrative purposes only and form no part of the claimed design.

1 Claim, 8 Drawing Sheets
